CLAIM

The ornamental design for a vehicle wheel, as shown and described.

DESCRIPTION

FIG. 1 is a perspective view of a vehicle wheel showing the claimed design;

FIG. 2 is a front view of that seen in FIG. 1;

FIG. 3 is a further perspective view of that seen in FIG. 1;

FIG. 4 is a perspective view of an alternate embodiment of

a vehicle wheel showing the claimed design;

FIG. 5 is a front view of that seen in FIG. 4;

FIG. 6 is a further perspective view of that seen in FIG. 4;

FIG. 7 is a perspective view of yet another embodiment of

a vehicle wheel showing the claimed design;

FIG. 8 is a front view of that seen in FIG. 7;

FIG. 9 is a further perspective view of that seen in FIG. 7;

FIG. 10 is a perspective view of still another alternate

embodiment of a vehicle wheel showing the claimed design;

FIG. 11 is a front view of that seen in FIG. 10; and,

FIG. 12 is a further perspective view of that seen in FIG. 10.

The broken lines in the drawings illustrate portions of the

vehicle wheel that form no part of the claimed design.
